UNITED STATES PATENT OFFICE.

GEORGE C. SNYDER, OF NEW YORK, N. Y.

FASTENING DEVICE.

Specification of Letters Patent. Patented Nov. 14, 1916.

1,204,711.

Application filed October 4, 1913, Serial No. 793,492. Renewed April 6, 1916. Serial No. 89,474.

To all whom it may concern:

Be it known that I, GEORGE C. SNYDER, a citizen of the United States, residing in the city of New York, county of New York, and State of New York, have invented certain new and useful Improvements in Fastening Devices; and I do hereby declare the following to be a full, clear, and exact description of the invention, such as will enable others skilled in the art to which it appertains to make and use the same.

The invention relates to fastening devices, especially of the button-type, and has for its object to provide a simple and efficient form of fastening which may be conveniently made of two pieces of spun, stamped, or pressed metal, which, when assembled, will constitute an open centered button or the like comprising a main body portion including a head and a tubular stem formed of a single piece of metal, and a thimble telescoping with the stem and coöperating therewith to form a shank inclosing an annular clamping space between the stem and thimble for the fabric to which the device is secured. In the preferred forms of the invention the outer shell of the shank, which may be either the stem, or the thimble, is provided with an out-turned flange, and the inner shell of the shank is projected beyond the edge of the outer shell to admit of the lower edge of the inner shell being turned outwardly to form a flange coöperating with the flange on the outer member and assist in clamping the device to the fabric.

In the accompanying drawings, Figure 1 is a vertical section through a button involving the invention; Fig. 2 is a vertical section through the thimble member of the fastening device; Fig. 3 is a vertical section through a button applied to a fabric; Fig. 4 is a vertical section through a modified form of button applied to a fabric; and Fig. 5 is a similar view of a further modification.

Referring to Figs. 1, 2 and 3 of the drawings, 1 indicates the head portion of a button, which may be formed of any suitable material, preferably non-corrodible metal, having an open center surrounding which

is a tubular stem 2, the upper portion of which is provided with an interior annular enlargement or offset to form a shoulder 3. Surrounding the hollow stem 2 and closely embracing the exterior portion of the enlargement is a cylindrical thimble 5 having its base terminating in a narrow outwardly turned horizontal flange 6, the thimble and the stem being so proportioned that the upper portion of the thimble tightly engages the outside of the upper portion of the stem, while the lower portion of the thimble is spaced laterally from the stem, thereby leaving an annular space 10 between the stem and the thimble, as clearly illustrated in Figs. 1 and 3. The lower end of the hollow stem 2 extends beyond the flange 6 on the thimble 5, as shown in Fig. 1.

A button of the type described is made by stamping the head 1 and hollow stem 2 from sheet metal or other suitable material and then applying a thimble of the form shown in Fig. 2 to the stem. By providing a close fit between the upper portion of the thimble and the enlarged portion of the stem, the two parts, when assembled by pressing the thimble over the stem, will not become disassociated and the complete button is sold with the parts so assembled.

When applying the device to fabrics, the fabric material is perforated at the point where the button is to be attached without, however, cutting out any portion of the material, and the portion of the material surrounding the punched opening is forced into the annular space 10 between the hollow stem 2 and the thimble 5 by any suitable means, such as a tubular mandrel or the like, after which the projected lower end of the stem 2 is turned outwardly to form a flange 4, see Fig. 3, substantially parallel with the flange 6 on the lower edge of the thimble. These various operations of punching the fabric, stretching the punched fabric over the hollow stem 2 and forcing the portion of the material surrounding the punched opening therein into the annular space 10, and finally turning the flange 4 on the lower end of the stem 2, may be conveniently effected by the machine

100

disclosed in a companion application filed of even date herewith.

When the button has been thus applied to a fabric, the latter will be securely gripped between the coöperating parts of the button, first, by the adjacent walls of the stem 2 and the thimble 5 defining the annular space 10; second, between the angles formed by the flanges 4 and 6 and the stem 2 and sleeve 5 which produces a very powerful snubbing action on the fabric, and third, between the flanges 4 and 6, so that the liability of the button tearing loose from the fabric is reduced to a minimum, even if the fabric is of the finest and sheerest character. The gripping action between the coöperating parts of the button and the fabric is clearly exemplified in Fig. 3, in which the fabric is shown as securely embraced between the walls forming the annular recess 10, into which space the fabric is stretched and forced, snubbed and compressed between the annular shoulders or angles defined by the flanges, and firmly gripped between the coöperating flanges 4 and 6.

In the modification shown in Fig. 4, the button head 1 is provided with an integral tubular stem 2', the upper portion of which is enlarged to provide an interior shoulder 3'. The lower edge of the stem 2' is provided with an out-turned flange 4'. In this form, the thimble is located within and coaxial of the stem 2', in which respect the button differs structurally but not operationally from that shown in the preceding figures, in which the thimble is located coaxially and exteriorly of the stem. In Fig. 4, the hollow thimble 5' is of less diameter than the lower portion of the stem 2' to provide an annular space 10 between the thimble and the stem, and the upper part of the thimble is enlarged to form an annular shoulder 5' which fits snugly into the corresponding shoulder 3' formed in the upper portion of the stem 2'. As manufactured and sold to the trade, the thimble 5' projects beyond the flange 4' on the stem and is adapted to be turned up by the means described in connection with the form of button shown in Figs. 1 and 3 to form a flange 6' when the button is applied to the fabric. It will be noted that the gripping action between the parts of the button and fabric is similar in all respects to that shown in the preceding figures, and the button is applied in a similar manner, as therein shown.

In certain types of fabrics, the binding or gripping action between the stem and the thimble, when the fabric is forced into the annular space 10, may be sufficient to secure the button to the fabric for all practical purposes, and in such cases, the flanges, such as 4 and 6, may be omitted. Such a form of button is illustrated in Fig. 5 which is simi-

lar in all respects to that shown in Fig. 4, with the exception that the flange 4' on the stem 2' is omitted, and the thimble 5' does not project or extend beyond the lower edge of the stem. In applying this type of button, the material is perforated and the edges thereof surrounding the perforation are forced and stretched into the annular space 10, after which the lower edge of the thimble 5' is expanded sufficiently to grip and compress the material against the adjacent wall 75

While the invention has been illustrated and described as applied to buttons, it is obvious that it is likewise applicable to other types of fastening devices, and in this respect, the button is to be regarded merely as exemplary.

What I claim is:—

1. A fastening device comprising inner and outer telescopic tubular members, one 85 of said members having a portion of reduced diameter extending throughout a part of its length to constitute with the other member an annular clamping space for the fabric to which the device is secured.

2. A fastening device comprising inner and outer telescopic tubular members having central openings extending completely therethrough, one of said members having a portion of reduced diameter extending 95 throughout a part of its length to constitute with the other member an annular clamping space for the fabric to which the device is secured.

3. A fastening device involving inner and outer members, one of said members comprising a button head having an integral tubular stem and the other member comprising a coaxial thimble telescoping with said stem, one of said members having a 100 portion of reduced diameter extending throughout a part of its length to constitute with the other member an annular clamping space for the fabric to which the device is secured.

4. A button involving inner and outer members, one of the same comprising a head and an integral tubular stem and the other comprising a coaxial thimble attached to said stem, one of said members having a 115 portion of reduced diameter extending throughout a part of its length to constitute with the other member an annular fabric clamping space, the end of the thimble extending beyond the stem and adapted to be 120 turned outwardly to form a clamping flange coöperating with the lower edge of the stem.

5. A button involving inner and outer members, one of the same comprising a head and an integral tubular stem having a flange 125 on the lower end thereof and the other comprising a coaxial thimble attached to said stem, one of said members having a

portion of reduced diameter extending throughout a part of its length to constitute with the other member an annular fabric clamping space, the end of the thimble extending beyond the stem and adapted to be turned outwardly to form a clamping flange coöoperating with the flange on the stem.

In testimony whereof I affix my signature, in presence of two witnesses.

GEORGE C. SNYDER.
